United States Patent Office

Des. 221,641
Patented Aug. 31, 1971

221,641

CHAIR

Morris F. Fisher, 9820 Deerfield Circle,
Carmel, Ind. 46032

Filed Apr. 23, 1970, Ser. No. 22,606

Term of patent 14 years

Int. Cl. D6—01

U.S. Cl. D15—1

Fig. 1

Fig. 2

FIG. 1 is a perspective view of a chair showing my new design, and directed downward and toward the front and one side of the chair; and

FIG. 2 is a perspective view directed downward and toward the rear and other side of said chair.

I claim:

The ornamental design for a chair, as shown.
